MOLTEN METAL SAMPLING TUBE

Rudolph J. Palme, Hamilton, Ontario, Canada, assignor
to Evacuo Enterprises Ltd., Hamilton, Ontario, Canada

Filed June 21, 1968, Ser. No. 12,471

Term of patent 14 years

Int. Cl. D24—99

U.S. Cl. D16—1

FIG. 1

FIG. 2

FIG. 1 is a perspective view of a molten metal sampling tube showing my new design; and

FIG. 2 is a perspective view of a modified embodiment of the sampling tube illustrated in FIG. 1.

I claim:

The ornamental design for a molten metal sampling tube, as shown and described.
